UNITED STATES PATENT OFFICE.

HARRY F. WAITE, OF NEW YORK, N. Y.

PLATE HOLDER AND INDICATOR THEREFOR.

1,404,171.

Specification of Letters Patent. Patented Jan. 17, 1922.

Application filed November 16, 1918. Serial No. 262,753.

To all whom it may concern:

Be it known that I, HARRY F. WAITE, a citizen of the United States, and a resident of Whitestone Landing, city of New York, county of Queens and State of New York, (whose post-office address is 252 West 29th Street, New York city,) have invented a new and useful Improvement in Plate Holders and Indicators Therefor, of which the following is a specification.

The object of my invention is to provide a suitable plate holder for dental films which may be placed in the mouth of a patient repeatedly and in any predetermined position with regard to the direction of propagation of X-rays so that when the device is in use, shadow pictures of parts may be repeatedly taken from the same position of the plate and uniform results obtained. A further object is to make a simple, reliable and durable holder which is suited to all dental requirements. These and other objects are accomplished by my invention, one embodiment of which is hereinafter more particularly set forth.

For a more particular description of my invention, reference is to be had to the accompanying drawings, forming a part hereof, in which:

Figure 1 is an edge view of my improved plate holder.

Figure 2 is a view taken at right angles to the view shown in Figure 1, to disclose the indicator.

Figure 3 is a sectional view taken on the line 3—3 of Figure 1, looking in the direction of the arrows.

Figure 4 is a plan view of the film holding portion with the indicator removed.

Figure 5 shows a portion of the indicator which is a reverse of the view shown in Figure 1.

Figure 6 shows the plate holder and indicator in position in a patient's mouth.

Throughout the various views of the drawings, similar reference characters designate similar parts.

My improved plate holder 1 consists of a base or film holding portion 2 on which is pivotally mounted an arm 3 which has a socket 4 rising from near its free end. It will be noted that this socket 4 has an opening 5 along its axis to receive a portion of an indicator and two plane surfaces 6

and 7 which are at right angles to each other.

An indicator 8 which rises from the projection 4 is secured in the following manner. It is provided with a circular pin 9 that rests tight and snug in the opening 5 and also with a small plate 10 which runs parallel to the pin 9 and rests against the surface 6 or the surface 7, according to the position in which it is placed. The parts 9 and 10 rise from a base 11 and run laterally therefrom. This base 11, at its end remote from the plate 10, has a pointer 12 extending in a plane that is parallel to the plane of the plate 10, and runs parallel with the plate 10 and then at an angle of 45 degrees or substantially this, as indicated. The pointer 12 carries a pivot 13 on which is mounted an angle plate 14 which is also pivotally mounted and provided with two dials, one on each face, one for the pointer 12 and the second dial 15 for a pointer 16 which is pivotally mounted at 17, as shown, and provided with a socket 18 which is adapted to receive a removably mounted orange-stick 19 or similar device, which when in use, rests in or near the X-rays and substantially parallel to their direction of propagation.

The two dials and two pointers 12 and 16 enable the dentist to set the stick 19 at any desired inclination to the film holding portion 2, and he may record this inclination by designating the two dials in any suitable way and the position of each pointer on this dial so that at any future date, he may again set this stick at any desired inclination.

The first time the device is used on a patient, as shown in Figure 6, the patient is properly placed in a chair and the X-ray tube also put in the desired location, as indicated, and then the film holder with a film mounted thereon and held between suitable guides on the part 2 is put in the patient's mouth at the desired location and held in the patient's mouth at the desired location and held by the patient or in any other suitable way and the orange-stick 19 is manipulated so as to be parallel to the extension on the X-ray tube (see Figure 6.) Exposure is then had in the conventional manner and a reading is taken and recorded, which shows the position of the respective pointers 12 and 16. At a future time, when a second picture is taken to show any changes that may have

occurred in the patient's condition, the plate holder has its indicator set from the record exactly the same as before, and then the plate holder is placed in the patient's mouth 5 as before. The X-ray tube is now adjusted until the orange-stick 19 lies parallel to the extension tube (see Figure 6.) Then a second picture is taken and the projection on the negative is exactly the same as the first 10 and any changes which may appear upon a comparison on the two negatives indicate a change in the patient's condition.

The arm 3 could be fixed to the film holder 2 if that were desirable, but it is not. The 15 preferred construction is shown in which this arm is pivoted at 20 and in the film holder 2 are placed two protuberances 21, either of which may be caused to register with a corresponding depression 22 in the 20 arm 3 so that this arm may be placed at either side according to whether the plate holder is to be used at the right or left of the patient.

In view of the foregoing, it will be understood 25 that my improved plate holder may be modified in various ways all of which come within the scope of this invention.

What I claim is:

1. In a plate holder, means for holding a 30 film and an indicator connected to the holder with means for enabling the indicator to be shifted to any predetermined angle with regard to the film holding means and means for indicating the inclination at which the 35 indicator is placed with regard to the film holder, whereby the indicator may be re-

placed at the same angle to the film holder when it is desired to reproduce the relations between them.

2. In a plate holder, means for holding a 40 film, an arm pivotally mounted on said film holding means and an indicator mounted on said arm and provided with means for permitting a shifting of the indicator to any predetermined angle with regard to the film 45 holding means.

3. In a plate holder, means for holding a 50 film and an indicator connected therewith so that it may be shifted to either side of the film holding means and set at any desired angle to the film.

4. In a plate holder, means for holding a 55 film, a pivoted arm mounted on said film holding means, and an indicator mounted on said arm by a suitable connection so that it may be held at any desired angle to the film.

5. In a plate holder, means for holding a 60 film and an indicator connected to said film holding means, said indicator being provided with an angle plate and pointers pivotally connected therewith, whereby the indicator may be set at a predetermined angle.

6. In a plate holder, means for holding a 65 film, protuberances on said means, an arm pivoted to said means and provided with a corresponding depression so that it may be held in either of two positions, a socket rising from said arm with a plane face and an indicator provided with a plate and pin adapted to engage said socket.

HARRY F. WAITE.
